HINGE

Dothan L. Shelton, Amarillo, Tex.

Application January 13, 1958, Serial No. 49,223

Term of patent 14 years

(Cl. D10—9)

Fig. 1 is a face view of a hinge, showing my new design; and

Fig. 2 is a side elevation thereof viewed at an angle parallel to the pintle of the hinge.

I claim:

The ornamental design for a hinge, substantially as shown.
